CLAIM

The ornamental design for a tire tread, as shown and
described.

DESCRIPTION

FIG. 1 is a side perspective view of a tire tread showing our
new design, it being understood that the pattern is repeated
throughout the circumference of the tire tread, the opposite
side being the same as that shown;

FIG. 2 is a front elevational view thereof;

FIG. 3 is a side elevational view of the right side thereof, the
opposite side being identical thereto; and,FIG. 4 is an enlarged fragmentary front elevational view
thereof.The dark stippled surface represents the recessed portion of
the tread grooves, having an indeterminate depth; the broken
lines defining the tire sidewall and inner bead and the
peripheral boundary between the tire and sidewall are for
illustrative purposes only and form no part of the claimed
design.
